Primary Examiner — Lauren R Calve*(74) Attorney, Agent, or Firm* — Richards Patent Law P.C.(57) **CLAIM**

The ornamental design for a locking container with a hinged compartment, as shown and described.

DESCRIPTION

FIG. 1 is a top, front perspective view of a locking container with a hinged compartment showing my new design;
 FIG. 2 is a bottom, rear perspective view thereof;
 FIG. 3 is a top plan view thereof;
 FIG. 4 is a right side elevational view thereof;
 FIG. 5 is a left side elevational view thereof;
 FIG. 6 is a front elevational view thereof;
 FIG. 7 is a rear elevational view thereof;
 FIG. 8 is an exploded top, front perspective view thereof; and,
 FIG. 9 is an exploded bottom, front perspective view thereof.
 The broken lines shown in the figures represent portions of the container that form no part of the claimed design.
